UNITED STATES PATENT OFFICE.

PRESTON R. BASSETT, OF BROOKLYN, NEW YORK, ASSIGNOR TO ELMER A. SPERRY, OF BROOKLYN, NEW YORK.

METHOD OF OPERATING FLAMING-ARC LIGHTS FOR PROJECTORS.

1,328,311.

Specification of Letters Patent. Patented Jan. 20, 1920.

Application filed December 18, 1916. Serial No. 137,743.

To all whom it may concern:

Be it known that I, PRESTON R. BASSETT, a citizen of the United States of America, residing at 1716 Newkirk avenue, Brooklyn, 5 in the county of Kings and State of New York, have invented certain new and useful Improvements in Methods of Operating Flaming-Arc Lights for Projectors, of which the following is a specification.

10 This invention relates to an improved method of operating a moderate amperage and moderate voltage high intensity direct current arc suitable for projector work. I refer to amperages of from 40 to 100 and 15 voltages of from 40 to 50 or thereabout. The basis of searchlight efficiency is primarily intrinsic brilliancy at the source. The object accomplished by this invention is the increase of the intrinsic brilliancy of the 20 positive crater to a point higher than can be obtained by either black body radiation or incandescence of any known material. While I am aware that high intensity flaming arcs have been obtained heretofore by 25 the method of operating outlined in the U. S. patent to Elmer A. Sperry, 1,227,910, dated May 22, 1917, such a method requires as a rule much greater power than an arc operated according to my invention. While 30 such method may be employed and the high intensity phenomena retained at comparatively moderate currents with good results, my invention furnishes an alternative or modified method of operation for moderate 35 currents (*i. e.* in the neighborhood of 40 to 90 amps.) which possesses the great advantage of burning at a much lower voltage than an arc operated according to said Sperry patent and thereby effect a saving in 40 power consumed, although at a slight sacrifice of candlepower.

Referring to the drawings which show diagrammatically the principle underlying my invention, Figure 1 is a side elevation of 45 a pair of flaming arc electrodes operating at a comparatively short arc length according to existing practices.

Fig. 2 is a similar view showing the behavior of the flame or flames at a greater 50 arc length.

Fig. 3 is a similar view of electrodes operating according to my invention.

Fig. 4 is a front view of the same.

Fig. 5 is a front view showing the effect 55 of increasing the arc length.

Both electrodes under this invention are preferably cored carbons. The positive electrode P comprises a pure carbon shell 1 and a core 2 the latter containing a mixture with carbon of light emitting salts to which the 60 intensified and at the same time the concentrated brilliancy is directly due. The negative electrode N also comprises a pure carbon shell 3 and a core 4 which is provided preferably with arc sustaining materials for 65 the major purpose of holding the negative spot at an unvarying point 8 of the negative carbon tip continuously and thereby prevent wandering thereof. For the sake of brevity, the electrodes may be referred to 70 as flaming arc electrodes.

Both carbons are run at moderate or even high current density, the positive electrode being in the neighborhood of $\frac{1}{2}$ an inch in diameter. In operating electrodes as above 75 described at the specified currents of from 40 to 90 amperes, it is found that the desired results cannot be obtained with any ordinary electrode arrangement used at the present time in searchlights. 80

In securing the desired results the problem has been to maintain the positive crater 7 continuously at what might be called abnormal brilliancy. The arc with ordinary electrode arrangement, such, for instance, as 85 is shown in Figs. 1 and 2 tends to be unsteady, and the positive crater at times fails to produce the high intensity "kernel" 9 characteristic of my invention and suddenly appears almost black instead of giving the 90 desired blue-white intense light. It is necessary, of course, that this "kernel" of intense light be permanent, dependable, and not sensitive.

I have discovered that in order to maintain this intense light at the low currents and voltages employed the following are important essentials: 95

1st. The impregnated core 2 of the positive electrode should be run at a current density at its crater face, which is higher than it would normally run, *i. e.*, the core face should be overloaded continuously so that if the arc were burned in the usual manner the flame would overflow and emanate from 100 the shell and especially the outer walls of the electrode tip. To accomplish this, I employ a small positive electrode and adjust the amount of this spindling of the shell so 105 that at the crater there is only enough shell 110

surrounding the core to prevent the oxidation of the core. In order to prevent the spindling from extending back too far I may employ a heat resisting and preferably 5 also insulating sleeve 11 to surround the electrode adjacent the arc of quartz or the like. This sleeve stops a predetermined distance back of the arc, as shown. It not only prevents oxidation and vaporization of the 10 carbon within, but also aids in maintaining the heat of the arc by preventing heat losses close to the arc.

2nd. In order to confine and maintain this current overload to the core face it is necessary to prevent the negative arc flame 5 from having any chance of touching other parts of the positive electrode. It should be confined to the crater face itself.

The crater forming a part of this invention, running at an abnormal current density 20 as it does, has a strong tendency to spread, thus reducing the current density to the normal figure at which figure the desired results are lost. Special steps should therefore 25 be taken to diminish the part played by the shell of the positive carbon in the formation of the arc proper. Marked spindling, preferably produced by oxidation is therefore important in causing the 30 core to protrude forward so that the flame may establish the necessary circuit relation, thereby, insuring the necessary energy concentration at the core face for producing the high intensity light spot or "kernel". In 35 fact the arc flame must not be allowed to touch parts of the electrode other than this core face, and the very thin protecting shell around the core face. My preferred method of accomplishing this result is to tilt the 40 negative carbon at a large angle. Figs. 1 and 2 show the tendency of this arc under ordinary conditions to arc from other portions of the positive electrode than the crater face, Fig. 1 showing the burning conditions 45 when a short arc is employed and Fig. 2 the conditions with the longer arc. By this or equivalent means the arc flame 5 which according to my invention appears to emanate almost entirely from the negative 50 electrode, passes almost vertically past the positive electrode as though nothing but the end of the core were present. The tip 8 of the negative is preferably positioned slightly below or in line with the core 2 of the positive. The end of the positive electrode is 55 preferably not allowed to be immersed in the arc flame, the contact for establishing the necessary circuit connection being reduced to the smallest dimension possible so 60 that only the comparatively flat protruding face of the positive core surrounded by a thin rim of the shell is touched by the flame (Figs. 3 and 4). In order to secure uniform tapering of the desired characteristics as 65 hereinafter specified, I prefer to rotate at

least the positive electrode though this is by no means necessary.

The electrode may be tilted as much as from 15 to 60 degrees below the horizontal, thus producing as stated an almost vertical 70 negative arc flame. This position of the arc flame is also important in maintaining an arc which is far less sensitive to the drafts of upwardly rushing air which always occur in arcs. The air thus moving lengthwise of 75 the arc flame does not disturb it nearly as readily as when passing at a substantial angle or crosswise to the length of the flame, as is the case in Fig. 1. This is especially true when either one or both of the electrodes are rotated, which tends still further to increase the sensitiveness of the arc to interruption, although a number of very valuable gains are made thereby, such as, maintaining a constant axial position of the 85 light source, as well as securing a uniform spindling of the electrode, and promoting such spindling as a concave curve 6, of the outer walls instead of a convex curve, as is usual with a carbon arc.

90 3rd. The third important factor in my invention relates somewhat to the second, as it has been found an effective aid in preventing the spreading of the crater. This is the use of a very short arc, say under $\frac{1}{4}$ of an 95 inch. If attempt is made to employ a short arc with the ordinary electrode arrangement, an arc such as shown in Fig. 1 is produced in which the negative flame envelops the tip of the positive.

100 With my arrangement, however, a low voltage arc is obtained with slow consumption of the positive electrode, which burns in such a manner as to cause definite spindling while presenting a very shallow crater 105 that in point of diameter closely approximates that of the core. In the operation of this arc a small high intensity spot of blue-white light is maintained at the positive crater, which as stated, is about coextensive 110 with the core of the electrode.

115 The advantage of the short arc with my electrode arrangement is that the particular portion of the flame which contacts with or finds itself supplying the sole circuit connection with the positive crater is of about the same diameter as such crater as shown in Fig. 4. This is indicated by the fact that if the arc be increased in length 120 the negative flame at the point of contact with the crater becomes wider than the crater (Fig. 5) causing unsteadiness, spreading of the arc, energy dissipation of the "kernel" and occasional periods of a "black crater".

125 Another advantage of the short arc is that it materially increases the stability of the arc and its resistance to drafts. In the direct current arc of from 40 to 90 amperes, the arc flame is of low velocity when com-

pared to arcs burning over 100 amperes. It is therefore most suitable to have as short a length of arc flame between the electrodes as possible, since it is very susceptible to air currents when the arc length is much longer than specified above.

- It is to be noticed that another radical difference exists between this high intensity arc and the forms previously known.
- 10 The latter, in fact, all other known high intensity arcs have an arc voltage higher than the ordinary arc, whereas this high intensity arc has an arc voltage lower than the ordinary arc—to illustrate:
- 15 The hereinbefore referred to "Sperry" high intensity arc burning from 70 to 200 amperes has an arc voltage of from 60 to 85 volts as compared to an ordinary arc voltage of this amperage of about 50 to 55 volts.
- 20 This new form of high intensity arc at amperes below 100 in one of its satisfactory embodiments has an arc voltage of only about 42 to 45 volts.

My invention is in many ways distinguished from the aforesaid Sperry light. Thus, in addition to not being applicable to currents sufficient to form a tongue in the negative flame, the voltage drop is decidedly lower even when the Sperry method is employed at moderate currents and the crater is very different. As explained above, nearly all of the shell is allowed to taper away by the time it reaches the tip so that practically only the core face forms the arc.

35 In addition no deep crater is necessarily formed, the core presenting a shallow concavity at its end of only sufficient depth to hold the bright kernel of the flame.

By employing the above new method of operating a searchlight arc, it is possible to double the intrinsic brilliancy obtainable with an ordinary arc with the same amperes flowing and at the same time use less power.

Having described my invention, what I claim and desire to secure by Letters Patent is:

1. The method of operating electrodes for projectors at moderate amperage in which the positive electrode is provided with a core containing light emitting admixtures which consists in causing such a spindling of said electrode that the crater face operates at an abnormal current density and in positioning the negative electrode at such

an angle to the positive that the negative 55 flame sweeps past said crater face without enveloping the electrode back of said face.

2. The method of operating electrodes for projectors at moderate amperage and voltage in which the positive electrode is provided with a core containing light emitting admixtures which consists in causing such a spindling of said electrode that the crater face operates at an abnormal current density and in positioning the two electrodes at 65 such an angle to one another that the negative flame touches the positive electrode only at said crater face.

3. The method of operating flaming arc electrodes at an amperage insufficient to 70 produce a negative tongue which consists in positioning the negative electrode at such an angle as to produce a substantially vertical arc flame and in so positioning the positive electrode that the crater face only 75 touches the flame.

4. The method of operating flaming arc electrodes at moderate amperage and voltage which consists in positioning the electrodes at an angle to one another so that the 80 negative flame sweeps past the positive electrode tip and touches said tip before said flame reaches its broadest portion.

5. The method of operating electrodes for projectors at moderate amperage in which 85 the positive electrode is provided with a core containing light emitting admixture, which consists in operating said electrodes at sufficient current density to cause such a spindling of the electrode that substantially 90 only the core is exposed at the arcing end, and in confining the crater to the exposed core face by positioning the two electrodes at such an angle so that the negative flame sweeps past the positive tip without enveloping it.

6. The method of operating flaming arc cored electrodes at an amperage insufficient to produce a negative tongue which consists in directing the negative flame at such 100 an angle as to produce a substantially vertical flame and in so positioning the positive electrode that the cored crater face touches said flame.

In testimony whereof I have affixed my 105 signature.

PRESTON R. BASSETT.
